UNITED STATES PATENT OFFICE.

RALEIGH DUNN, OF GERVAIS, OREGON, ASSIGNOR OF ONE-HALF TO GEORGE W. DUNN,
OF GERVAIS, OREGON.

DOORLOCK.

Application filed July 10, 1925. Serial No. 42,862.

This invention relates to a lock for sliding doors, the general object of the invention being to provide a lock, the parts of which will be entirely enclosed in the doors. 5 when the bolt is retracted so that there will be no projections to catch and damage garments of persons passing between the doors. 10 Another object of the invention is to provide means whereby a bolt on one door will engage a latch member carried by the other door, with means on one door for operating the bolt and means on the other door for operating the latch member.

A further object of the invention is to 15 provide a key operated member for locking the latch member in latching position.

This invention also consists in certain other features of construction and in the combination and arrangement of the several 20 parts, to be hereinafter fully described, illustrated in the accompanying drawings and specifically pointed out in the appended claims.

In describing my invention in detail, 25 reference will be had to the accompanying drawings wherein like characters denote like or corresponding parts throughout the several views, and in which:—

Figure 1 is a view through the two parts 30 of the lock, with the cover plates removed therefrom.

Figure 2 is a section on line 2—2 of Figure 1, and showing the lock parts in the door.

Figure 3 is a section on line 3—3 of Figure 2.

Figure 4 is a perspective view of the latch proper.

Figure 5 is a view of the locking bar of 40 the latch member.

Figure 6 is a view of the key for operating said bar.

In these views, 1 indicates a casing which is adapted to be placed in the door A and 45 2 indicates a casing which is adapted to be placed in the companion door B. An L-shaped bolt 3 is carried by the casing 1 and said bolt is provided with a latch head 4 and an L-shaped slot 5 which is engaged by 50 a pin 6 carried by the casing. The bolt is provided with the rack teeth 7 which extend along a part of the upper horizontal edge thereof and down along the vertical edge thereof, and these teeth are engaged by 55 a pinion 8 on the knob stem 9, the knob of

which is shown at 10. A block 11 is arranged in the casing and carries a spring 12 which bears against the bolt and tends to hold the same in horizontal position, as shown in full lines in Figure 1. When the 60 knob is turned, the pinion, engaging the rack teeth, will first cause the bolt to be tilted by forcing its inner end downwardly and then the bolt will be moved rearwardly on an incline, as shown in dotted lines in 65 Figure 1, the bolt being guided by the pinion 6 engaging the L-shaped slot 5. Thus the bolt will be retracted. A block 13 is arranged in the top part of the casing and engages the upper edge of the bolt and also 70 acts as a stop for the same by being engaged by a projection 14 on the bolt. The lower edge of the bolt is recessed, as at 15 for engaging the bottom wall of the opening in the case when the bolt is in projected 75 position. This arrangement firmly holds the bolt against play when in projected position.

The casing 2 carries a latch member 16 which is pivotally supported in the casing by means of the tubular projections 17 80 thereon engaging bearing openings in the casing and in its cover. This latch member is provided with a latch part 18 for engaging the latch head 4 of bolt 3 so as to inter-lock with the bolt and said latch member 16 is held in latching position by the spring 19 which tends to hold a shoulder 20 on the rear part of the latch member against the stop pin 21 in the casing. The latch member is rocked by a knob stem 22 85 passing through the casing and having the knobs 23 attached thereto.

In order to hold the latch member in its upper or latching position, I provide a sliding block 24 which engages the under part 95 of the latch member and prevents it from being lowered. This block is slidably mounted on a guiding strip 25 which is provided with a groove 26 and an opening 27, one end of the opening registering with the 100 keyholes 28 in the casing so that the key will enter this space. The block is provided with a slot 29 which receives a pin 30 carried by the casing and the upper end of the block is provided with a pair of rounded shoulders 105 31 for engaging the rounded end of a spring 32 carried by a block 33 which will hold the block 24 in either its projected or retracted positions. The lower edge of the block is provided with a projection 34 and 110

the rack teeth 35 which engage the groove 26 in the strip 25 and the key 36 is formed with a pinion 37 for engaging the rack teeth 35 so that when the key is turned, the pinion engaging the teeth, will slide the block 24 to projected or retracted position.

From the foregoing, it will be seen that with the block 24 retracted, the latch member 18 will give and move downwardly under 10 the pressure exerted thereon by the beveled end of the bolt 3, as the doors come together and the bolt is in projected position or if the bolt is projected after the doors have been closed. This will lock the doors together and if they are to be opened, it will be necessary to lower the latch member 18 before the doors can be opened. The latch member is lowered by the turning of the 15 knob stem 22, but this cannot be done if the block 24 is in projected position. In this case, it will be first necessary to retract the block by means of the key before the latch member can be lowered. Then by turning the knob stem 9, the bolt 3 can be retracted to its dotted line position shown in 20 Figure 1, so that there will be no projecting parts from the edges of the doors.

It is thought from the foregoing description that the advantages and novel features 30 of my invention will be readily apparent.

I desire it to be understood that I may make changes in the construction and in the combination and arrangement of the several parts, provided that such changes fall within 35 the scope of the appended claims.

What I claim is:—

1. A lock of the class described, comprising a pair of casings, a bolt in one casing, a latch member in the other casing engaging the bolt when the same is projected; means 40 for manipulating the bolt, means for manipulating the latch member, key operated means for locking the latch member in latching position, such means comprising a sliding block, a spring for holding it in either 45 its projected or retracted position, rack teeth on the block and a key having a pinion thereon for engaging the rack teeth.

2. A lock of the class described, comprising a pair of casings, a bolt in one casing 50 having an L-shaped slot in one end, a latch head on the other end, a pin in the casing and disposed in said slot, manually operated means having engagement with the bolt for moving the same in the casing, shoulders on 55 opposite sides of the bolt adapted to engage means on the casing to limit the movement of the bolt in one direction, a latch member in the other casing engaging the bolt when the same is projected; means for manipulating the latch member, key operated means for locking the latch member in latching position, such means comprising a sliding block, a spring for holding it in either 60 its projected or retracted position, rack teeth on the block and a key having a pinion thereon for engaging the rack teeth.

In testimony whereof I affix my signature.

RALEIGH DUNN.
